United States Patent Office

Des. 212,937
Patented Dec. 17, 1968

212,937

MULTIPLE FAMILY DWELLING

John M. La Fata, Warren, Mich., assignor to Karem Brothers, Inc., Warren, Mich., a corporation of Michigan

Filed Feb. 15, 1968, Ser. No. 10,583

Term of patent 14 years

(Cl. D13—1)

FIGURE 1 is a partial front elevational and a partial rear elevational view of a multiple family dwelling embodying my novel design.

FIGURE 2 is a symmetrical partial elevational view of the ends of a multiple family dwelling embodying my novel design.

I claim:

The ornamental design for a multiple family dwelling, as shown.
